(57) **CLAIM**

The ornamental design for a wine cup, as shown and described.

DESCRIPTION

FIG. 1 is a top perspective view of a wine cup, showing the new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof, the right side elevation view being a mirror image of the left side elevation view;

FIG. 7 is a bottom perspective view thereof;

FIG. 8 is a top perspective view thereof with the lid removed;

FIG. 9 is a cross-sectional view of the wine cup shown along line 9-9 in FIG. 2;

FIG. 10 is an exploded top perspective view of the wine cup;

FIG. 11 is an exploded front elevation view of the wine cup;

FIG. 12 is an exploded rear elevation view of the wine cup; and,

FIG. 13 is an exploded right side elevation view of the wine cup.

The broken lines in the drawings depict portions of the wine cup that form no part of the claimed design.

1 Claim, 13 Drawing Sheets
